UNITED STATES PATENT OFFICE.

EDWIN LUNDGREN, OF PITTSBURGH, PENNSYLVANIA, ASSIGNOR TO WESTINGHOUSE ELECTRIC & MANUFACTURING COMPANY, A CORPORATION OF PENNSYLVANIA.

MECHANICAL STOKER.

1,406,199.

Specification of Letters Patent. Patented Feb. 14, 1922.

Application filed June 16, 1917. Serial No. 175,202.

To all whom it may concern:

Be it known that I, EDWIN LUNDGREN, a subject of the King of Sweden, and a resident of Pittsburgh, in the county of Allegheny and State of Pennsylvania, have made a new and useful Invention in Mechanical Stokers, of which the following is a specification.

This invention relates to mechanical stokers and especially to stokers of the inclined type in which fuel moves from the front downwardly toward the rear of the furnace as it passes through progressive stages of combustion.

It is well known that the capacity of a furnace is in a great measure limited by the active grate area. By the term "active grate area" I mean the area of the fuel supporting elements which are effective in delivering air, for the purpose of maintaining combustion of the fuel supported on them.

An object of my invention is therefore the production of a mechanical stoker in which means are employed for increasing the active grate area.

A further object is to produce a dump grate mechanism, adapted for use in connection with mechanical stokers, in which improved means are employed for delivering air under pressure to the fuel supporting elements of the mechanism.

A further object is to produce a dump grate mechanism in which new and improved means are employed for delivering air under pressure to the mechanism and for cooling the fuel supporting elements of the mechanism.

A further object is to produce a mechanical stoker in which improved means are employed for varying the air supply to different portions of the fuel bed maintained on the fuel supporting elements of the stoker, so that the stoker will operate with high efficiency throughout a wide range of loads.

These and other objects, which will be made apparent throughout the further description of the invention are attained by means of apparatus embodying the features herein described and illustrated in the drawings accompanying and forming a part hereof.

In the drawings: Fig. 1 is a longitudinal

sectional view of a stoker embodying my invention taken along the line A—A of Fig. 2.

Fig. 2 is a plan view of the stoker illustrated in Fig. 1.

Fig. 3 is a sectional view of a fuel supporting element forming a detail of the present invention.

Fig. 4 is a plan view of the element shown in Fig. 3.

Fig. 5 is a sectional view of the element illustrated in Fig. 3, shown in connection with cooperating supporting and air delivering elements.

Fig. 6 is a sectional view taken along the line 6—6 of Fig. 5.

Fig. 7 is a diagrammatic plan view illustrating the operative connections between the fuel feeding plunger and the reciprocating overfeed section which form details of the present invention.

Fig. 8 is a fragmental longitudinal sectional view of a modified form of dump grate mechanism which forms a part of my present invention.

Fig. 9 is a sectional view of an overfeed section forming a detail of the apparatus illustrated in Fig. 8.

The stoker illustrated in Fig. 1 includes a hopper 10, to which fuel may be delivered by any suitable means. The hopper communicates with the ram box 11, in which a ram 13 operates for the purpose of feeding fuel, discharged from the hopper, into the furnace, or onto the fuel supporting elements of the mechanical stoker.

The stoker illustrated in Figs. 1 and 2 includes longitudinally arranged retorts 14 and combined fuel supporting and air delivering elements 15, which extend from the front downwardly toward the rear of the furnace and constitute the underfeed portion of the stoker. Each retort is fed by one of the rams 13 and communicates at its upper end with the discharge opening of the ram box. As illustrated, each retort consists of a floor 16 and the sidewalls or bars which support the elements 15. The elements 15 are illustrated as being made up of separate twyer blocks 17 located in overlapping relation and each being provided with air delivery openings or passages, adapted to deliver air laterally into the fuel as it issues

from the retorts. The twyer blocks are also provided with openings adapted to deliver air rearwardly and into and through the fuel supported on the twyer blocks. The air 5 delivered by the twyer blocks is received through a transversely extending air trunk 18, which communicates with and delivers air to the passages located between the retorts and bridged by the twyer blocks 17. 10 Fuel fed into the retorts by the rams 13 is forced out of the retorts and onto the twyer blocks by the continual fuel feeding action of the rams. This crowding action imparts a downward motion to the fuel constituting 15 the fuel bed.

In order to ensure complete combustion of the fuel issuing from the underfeed portion of the furnace, I have shown an overfeed portion made up of separate sections which 20 are adapted to reciprocate and to aid the rearward movement of the fuel as it passes through the progressive stages of combustion.

As illustrated, each section of the overfeed 25 portion includes a frame member 20 (see Fig. 5) which is slidably mounted on the inclined portion of a box support or bracket 21 (see Fig. 1).

The bracket 21 preferably embodies compartments arranged therein to supply air 30 to the overfeed section and the ash discharge mechanism. The bracket 21 is also the chief support for the ash discharge mechanism as hereinafter described (see Fig. 8). 35 Each overfeed section also includes overlapping grate bars 23, which are mounted on the frame 20 and are locked in their mounting position by means of a locking member 24, which is detachably secured to 40 and forms the rear end of the frame 20. As shown in Fig. 5, the bolt 24' extends through coacting lugs on members 20 and 24 to secure said members as a unit. Each grate bar extends from the front to the rear edge of 45 the frame, and its forward end is held in place by engagement with an inwardly projecting flange 26 formed on the frame. The rear end of each grate bar engages a supporting and lock flange 26^a formed on the 50 locking member 24.

Each grate bar 23, is formed in steps, and air ports 28, are formed near the base of each riser of each step. In order to prevent ash or other material from working back 55 through these air ports and into the frame portion, I have provided a forwardly and upwardly projecting flange 29, which is located on the air admission side of each set of ports. The grates are also provided with 60 longitudinally extending strengthening ribs 30, which serve the double purpose of preventing the bars from warping and at the same time provide ash retaining pockets which protect the bars from the heat of 65 combustion within the fire box.

As shown, the support 21 constitutes a part of the frame proper of the stoker, and the portion on which the overfeed sections are mounted is inclined downwardly toward the rear of the furnace, so that the reciprocating motion of these sections is in substantially the direction of the plane of inclination of the fuel bed. In the apparatus illustrated this motion is imparted to the separate sections of the overfeed portion by means of rods 31 which are attached at their lower ends to brackets 32 formed on or secured to the frames 20, and at their upper ends to the rams 13. An adjustable lost motion connection is employed between each ram and each rod, so that the reciprocatory motion of the overfeed sections may be adjusted to suit the desired conditions of fuel feed. The connection consists of a pin 33, which is secured to the ram and which projects through slots formed in the ram guide. The forward ends of the rods project through suitable openings formed in the pins, and the motion imparted to each rod is dependent on the position of an adjustable nut 34 with relation to a shoulder 35 formed on the rod. 70 75 80 85 90 95

The fuel from the overfeed section is fed on to a dump grate mechanism, which is located between it and the bridge wall of the furnace. As illustrated in Figs. 1 and 2, the mechanism is a double leaf dump mechanism, or includes two dump grates so arranged that the movable edges of the grates are adjacent to each other. 100

The forward grate 47 is mounted on the support member 21, which, so far as this grate is concerned, performs the function of a supporting bracket. The construction of the grate 47 is similar in some respects to that of the overfeed section in that it includes a frame 48 in which overlapping grate bars 45 are removably mounted. As illustrated, the frame 48 is mounted on a shaft 48^a which is suitably journaled on the bracket 21. The forward edge of the frame 48 is provided with a cylindrical face to accommodate the turning motion of the frame about the axis of the shaft 48^a. The grate bars 45 are removably secured to the frame by means of a removable locking member 51 and are similar in construction to the bars 23. The means employed for securing these bars to the frame 48 is similar to the means employed for securing the bars 23 to the frame 20. 110 115 120 125 130

The rear grate 52 of the dump grate mechanism is mounted on shaft 53, which in turn is suitably mounted on the bridge wall 54. Both the grate 47 and the grate 52 are adapted to be swung downwardly, from the position shown in Fig. 1, to substantially vertical positions for the purpose of dumping the accumulation of ash and clinker delivered to them from the overfeed section. 135

The actuating mechanism of the grate 52 is diagrammatically illustrated by means of a ratchet controlled lever 55, which is rigidly mounted on the shaft 53 and is located at 5 one side of the furnace.

The operating mechanism of the dump grate 47 includes a suitably journaled shaft 56, a lever 57 rigidly mounted on the shaft and a link connecting the free end of the 10 lever to the free edge of the grate 47. It also includes a worm gear 58, located at one side of the stoker and rigidly mounted on the shaft 56, and an actuating worm 59 which meshes with the worm gear. With 15 this arrangement of operating mechanisms either the grate 47 or the grate 52 may be moved to the vertical or complete dumping position, or may be moved to intermediate positions between the dumping position and 20 the position shown in Fig. 1.

The dump grate 47 is provided with an air delivery passage 61, which is located between the grate bars 45 and the lower wall of the frame 48. The grate bars 45, like the 25 bars 23, are in the form of steps, and the riser of each step is provided with a series of air delivery ports 46^a which communicate with the passage 61 and which are adapted to deliver air to the fuel or mix- 30 ture of fuel and ash on the dump grate. Air under pressure is delivered to the chamber 61 through ports 62, formed in the cylindrical face of the frame 48 and registering with correspondingly spaced ports 35 formed in the bracket 21. The bracket 21 is provided with two air delivery passages 63 and 64. The passage 63 delivers air to the grate bars 23 of the overfeed section through registering ports formed in the up- 40 per face of the bracket and in the lower face of the frame 20. The passage 64 communicates with the ports 62. Air under pressure is delivered to the passages 63 and 64 from the air duct 18, which receives air under 45 pressure from a damper controlled conduit 65. A regulable damper 66 is interposed between the duct 18 and the inlet ends of the passages 63 and 64. In addition to this, each passage is provided with a separate 50 controlling damper 67. All these dampers may be controlled by suitable means located either at the front or side wall of the furnace and consequently the air supply to the different fuel supporting elements may be 55 controlled independently. The damper 66 not only controls the delivery of air to the passages 63 and 64, but also controls the delivery of air to the lower portion of the underfeed portion, as is clearly described in 60 Patent No. 1,220,161 of March 20, 1917. With this arrangement, the delivery of air to the overfeed section and to the dump grate 47 may be controlled simultaneously with the control of air to the lower portion 65 or the air supplied to each of these fuel sup-

porting elements may be controlled independently by adjusting the damper 66 and each of the dampers 67.

In Fig. 8, I have illustrated a modified arrangement of overfeed portion and dump 70 grate mechanism. In this view the overfeed portion is mounted on the inclined face of the bracket 21 and consists of a frame 68, which supports grate bars 69 located in overlapping relation from the front to the 75 rear of the furnace.

These grate bars, unlike the bars 23, extend transversely of the direction of the movement of the fuel across the overfeed section and are supported at their lateral 80 edges by the upwardly projecting edges of the frame 68. The uppermost grate bar 69 is provided at each lateral edge with a depending L-shaped lug 70, each of which is adapted to engage an inwardly projecting 85 lug 71 formed on the frame 68 and to be engaged by the rear edge of the adjacent grate bar. With this arrangement the uppermost bar is locked in position on the frame and is held against forward movement by an 90 abutment 72 formed on the forward edge of the frame 68. The intermediate grate bar is of similar construction except that it is held between the lugs 70 of the topmost bar and the rear edge of the lowermost bar. 95 The lowermost bar forms the locking member for the other bars. It is also provided with the frame engaging lugs 70 but, inasmuch as these lugs are not engaged by the rear edge of an adjacent grate bar, some 100 means must be provided to prevent the bar moving with the fuel passing over the underfeed portion. As illustrated, each bottom grate bar is locked against downward 105 movement by means of two pins 73, each of which passes through the fuel supporting face of the bar and engages one of the lugs 71 of the frame. With this arrangement the grate bars 69 may be readily assembled 110 on the frame and they may be as readily removed therefrom, since the pins 73 are in effect removable locking pins which hold the cooperating grate bars in place.

The grate bars and the frame form a hollow fuel supporting element, the interior of 115 which constitutes an air delivery passage. Air is delivered to this passage through a port 68^a which registers with a port 74 formed in the frame supporting face of the bracket 21 and communicating with the passage 63 formed in the bracket. The upper or fuel supporting faces of the bars 69 are corrugated, and the lower face at a point adjacent to the rear edge of each of the bars, with the exception of the lowermost 120 bar, is also corrugated, so that these lower corrugations form air delivering passages 125 which receive air from the air passage located within the frame 68. The lowermost grate bar is provided at its rear end with a 130

downwardly turned nose 75, having ports 75^a formed therein which receive air from the interior of the frame.

The dump grate mechanism illustrated in Fig. 8 includes two dump grates like the mechanisms illustrated in Figs. 1 and 2, but each dump grate receives air under pressure. The makeup of each dump grate is similar to the makeup of each overfeed section in 10 that the dump grate is made up of a number of frames 76, on which transversely extending grate bars 77 are mounted. The grate bars 77 are secured to their mounting frames in the same way that the grate bars 69 are 15 secured to the frame 68, except that the pins 73 are replaced by bolts 78, which are rigidly secured to the lowermost grate bar and to the frame 76. The operating mechanism of each grate is similar to the operating 20 mechanism described in connection with the grate 47 of Fig. 1. Air is delivered to the forward grate as described in connection with the grate 47 through the passage 64 formed in the bracket 21. In Fig. 8, the arrangement 25 of the air ports 62 is more clearly illustrated and it will be apparent that these ports move into register with ports 79 formed in the bracket and communicating with the passage 64 when the grate is raised to the fuel supporting position illustrated in 30 Fig. 8. The rear grate receives air from an air passage 80 built into the bridge wall 54. The construction of this passage 80 is similar to that of the passage 64 and air is delivered to this grate in substantially the same 35 way that it is delivered to the forward grate of the dump mechanism.

It will be understood that for convenience of assembling, the overfeed portion of the 40 furnace is assembled in sections which are substantially equal in width to the distance between retort centers. Each of these sections includes one of the frames 68 in apparatus illustrated in Fig. 8, or one of the 45 frames 20 in apparatus illustrated in Figs. 1 and 2. These sections are consequently independently movable and inasmuch as the fuel feeding rams to which they are individually operatively connected do not move in 50 unison, it will be apparent that some of the sections are moving in one direction while others are moving in the reverse direction.

For convenience of manufacture and also for convenience of assembling the dump 55 grate mechanism is also divided into sections, each of which includes a frame and its supported grate bars. These sections are preferably of the same width as the sections of the overfeed portion of the furnace and 60 in wide furnaces it is desirable to divide them so as to form two or more dump grate mechanisms, each of which is independently operable.

While I have described and illustrated 65 several embodiments of my invention, it will

be apparent to those skilled in the art that various changes, modifications, additions, and omissions may be made in the apparatus described and illustrated without departing from the spirit and scope of the invention, 70 as set forth by the appended claims.

What I claim is:

1. In combination with a progressive feed furnace grate, a discharge mechanism at the lower edge of the grate comprising a hollow 75 swinging dump grate having an air chamber therein adapted to supply air at the dump grate surface, an air supply chamber adjacent the dump grate, and means along the lateral edge of the dump grate for receiving 80 air from the supply chamber.

2. In combination with a progressive feed furnace, an ash discharge apparatus at the rear of the furnace comprising hollow dump grates pivotally mounted at one edge, an 85 air distributing chamber adjacent the dump grates at the pivoted edges, detachably secured grate bars arranged to form air-admitting fuel-supporting surfaces of the dump grates, and means for delivering air 90 from the air distributing chamber to the hollow dump grates.

3. In combination in a mechanical stoker, an underfeed portion, an overfeed portion receiving fuel therefrom, consisting of relatively movable frame members reciprocable in substantially the line of travel of the fuel, a dump mechanism for receiving the fuel delivered from the overfeed section and comprising a hollow swinging grate having air 100 delivery passages formed in the upper wall thereof, means for delivering forced draft to said underfeed portion, said overfeed portion and said dump grate, and means for controlling the delivery of forced draft to 105 each of said elements.

4. In combination in a mechanical stoker, a series of hollow relatively movable overfeed grate sections having air delivery passages in the fuel supporting walls thereof, 110 oppositely disposed swinging hollow dump grates receiving fuel therefrom and having air delivery passages in the fuel supporting walls thereof, means for delivering forced draft to the interior of said grates and the 115 overfeed grate sections, and means for automatically shutting off the air to the dump grate when the latter is discharging clinker and ash.

5. In combination in a mechanical stoker, 120 a series of relatively movable overfeed grate sections, a dump grate receiving fuel delivered therefrom, means for delivering forced draft to said dump grate and to said grate sections, means for independently controlling the delivery of forced draft to said dump grate and said grate sections, and means for shutting off the air to the dump 125 grate when said grate is discharging clinker and ash.

6. In combination in an inclined underfeed stoker, a plurality of inclined retorts alternating with rows of air supplying means, means for feeding fuel into said retorts, a series of independently movable overfeed grate sections having air delivery passages therein, and a dump grate having an air delivery passage formed therein, means for delivering forced draft through said 10 air supplying means, through said air delivery passages of the overfeed grate sections and through the air delivery passage of said dump grate to the fuel bed, and means for controlling the delivery of forced draft through each of said elements. 15
7. In combination in a stoker, a swinging double leaf dump grate mechanism comprising oppositely disposed hollow grates each having air delivery passages in the fuel supporting walls thereof, means for delivering forced draft under pressure to the interior of said hollow grates, and means for shutting off the supply of air when the dump grate mechanism is discharging clinker and 20 ash. 25
8. In combination in a stoker, a plurality of inclined retorts alternating with rows of air supplying means, means for feeding fuel into said retorts, a series of relatively movable overfeed grate sections having air delivery passages therein, regulable means for imparting motion to each grate section, a dump grate mechanism receiving fuel from the grate sections, independently regulable 30 means for delivering air under pressure through said air supplying means, the said air delivery passages in the underfeed grate sections and said dump grate to the fuel bed. 35
9. In combination with an underfeed 40 stoker, an inclined overfeed grate adapted to receive fuel from the underfeed portion of the stoker, a hollow ash discharge mechanism at the lower end of the overfeed grate, said overfeed grate consisting of a frame having 45 a bottom portion and side and end portions arranged to form an air chamber, detachable grate bars having air delivery passages therein supported upon the side and end portions, means for locking said bars to said 50 side and end portions, means for independently delivering air under pressure to said chamber and the discharge mechanism and means for diminishing and shutting off the supply of air to the dump grate when the 55 latter is lowered to discharge clinker and ash. 60
10. In combination in an underfeed stoker, an inclined underfeed grate, a hollow reciprocable overfeed grate receiving fuel and ash from the underfeed grate, a hollow 65
- swingng dump plate for receiving fuel and ash from the overfeed grate, and means for separately delivering air to the interior of the overfeed grate and the interior of the dump plate. 70
11. In combination in a stoker, an underfeed section, an overfeed section, and a dump grate successively receiving fuel to be burned and each provided with air passages for delivering air to the fuel, means for delivering air under pressure to air passages of each of the sections and the dump grate, means for separately controlling the delivery of air to the overfeed section and the dump grate, and means for jointly controlling the 75 delivery of air to the overfeed section and the dump grate. 80
12. In combination in a stoker, a double leaf hollow swinging dump grate, each leaf having an air inlet port, and a plurality of air delivery ports, and means for delivering air under pressure to each leaf and for cutting off the supply of air when the grate is swung to its lowest position. 85
13. Stoking mechanism comprising in combination a supporting grate, a hollow dump grate cooperating therewith provided with an air admission port and adapted to be swung into open position, an air chamber provided with a port adapted to register 90 with the port in the dump grate when the dump grate is in closed position and to be closed by the dump grate when the said grate is swung into open position. 95
14. In combination in a stoker, a swinging dump grate mechanism comprising a hollow grate having air delivery passages in the fuel supporting walls thereof, means for delivering forced draft under pressure to the interior of said hollow grate, and means for automatically shutting off the supply of air 100 when the dump grate mechanism is discharging clinker and ash. 105
15. In combination in an underfeed stoker, an inclined underfeed grate, a hollow reciprocable overfeed grate receiving fuel and ash from the underfeed grate, a hollow swinging dump plate for receiving fuel and ash from the overfeed grate, and means for separately controlling the delivery of air to 110 the interior of the overfeed grate and to the interior of the dump plate.

In testimony whereof, I have hereunto subscribed my name this 9th day of June, 1917.

EDWIN LUNDGREN.
